B. L. DALL

FOUNTAIN PEN FILLER

Filed March 23, 1923

Fig. 1.

Fig. 2.

Fig. 3.

Inventor:

Benjamin L. Dall,
By Duly-Appointed
Attorneys.

UNITED STATES PATENT OFFICE.

BENJAMIN L. DALL, OF CHICAGO, ILLINOIS.

FOUNTAIN-PEN FILLER.

Application filed March 23, 1923. Serial No. 627,191.

To all whom it may concern:

Be it known that I, BENJAMIN L. DALL, a citizen of the United States, residing at Chicago, in the county of Cook and State of Illinois, have invented a new and useful Improvement in Fountain-Pen Fillers, of which the following is a specification.

This invention relates to a filler for fountain pens and is fully described in the following specification and shown in the accompanying drawings in which;

Figure 1 is a longitudinal section through the ink reservoir.

Fig. 2 is a partial section of the same as applied to a fountain pen during the act of filling and

Fig. 3 is a same view of a modified form of tube.

The embodiment illustrated consists of a tubular member 10 closed at one end and having a screw thread 11 formed in the opposite end which may be adapted to fit the threads 12 of a fountain pen 13 which are commonly used for securing a cap therein.

An outwardly flaring circular shoulder 14 is secured within the tube 10 in such a position as to engage the circular end 15 of the fountain pen when the latter is screwed into the end of the tube.

The pen is provided with some form of self filling device such as an operating lever 16 pivoted on a pin 17 and having a lower end 18 adapted to press inwardly on a metal bar 19 which lies along the rubber tube 20.

This is a well known form of self filling pen which is ordinarily filled by moving the lever 16 outwardly to dotted line position thereby collapsing the rubber tube 20, inserting the pen point into ink so that the lower end 15 is submerged and returning the lever 16 to full line position thereby permitting the collapsed tube 20 to expand and draw ink up filling the same.

With my device the tube 10 is filled with ink nearly up to the collar 14, and this is retained by a plug 21 having threads 22 which screw into the threads 11 and a conical end 23 which engages the internally tapered collar 14. If desired, a clip 24 may be secured to this plug so that the tube may be more readily carried in the pocket.

When the user finds that the supply of ink in his pen is running low, he removes the plug 21 from the tube, inserts the point of the fountain pen in the tube, and raises the

lever 16 to dotted line position and screws the fountain pen down against the collar 14. This is done with the tube 10 held in an upright position. The pen and tube are now inverted so that when the lever 16 is again depressed to the full line position ink will flow into the tube 20 due to the suction therein and assisted by gravity.

I prefer to make the tube 10 of a transparent or at least a translucent material so that the user can see how much ink flows into the pen and when the flow has ceased. When this occurs, the tube is again turned to its original upright position and the fountain pen removed and the plug 21 replaced.

This permits the user to carry with him a supply of ink and insures that the quality of his ink will always be uniform thereby preventing a great deal of bother resulting from deposits formed due to mixtures of various kinds of inks.

The form shown is one in which a special tube is designed to be used with a particular form of pen having screw threads 12 at a fairly definite distance from the end 15. In Fig. 3 is shown a modified form of the device in which the tube 10 is made large enough to admit the ends of a number of sizes of fountain pens which, however, engage only tapered collar 14^a and are held against it during the filling operation by hand. The operation of the device is otherwise the same as previously described.

While I have shown and described but a few embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as possible in view of the prior art.

What I regard as new and desire to secure by Letters Patent, is:

1. A filler adapted to fill the barrels of fountain pens comprising a hollow tube to contain ink and open at one end, and a hollow tapered downwardly converging collar in said tube adjacent its open end and adapted to be closed by the end of the barrel of the pen so that when the hollow ink-containing tube is inverted the ink therein will be fed to said barrel, said tube having threads thereon engaging

100

110

2
threads on the end of said barrel and to hold the end thereof against said collar, and a plug for closing said tube.

2. A filler for use with fountain pens which are filled through the end of the barrel comprising a hollow tube adapted to contain ink and open at one end, and a hollow tapered downwardly converging collar in said end flaring outwardly and adapted to be closed by the end of the barrel so that when the filler is inverted, ink therein may be fed to said barrel, said tube and barrel being provided with complementary threads adapted to hold the end of said barrel against said hollow tapered collar, and a plug adapted to seat within said tapered collar for closing said tube.

3. A filler for use with fountain pens which are filled through the end of the barrel comprising a hollow tube adapted to contain ink and open at one end, and a hollow tapered downwardly converging

collar in said end flaring outwardly and adapted to be closed by the end of the barrel so that when the filler is inverted, ink therein may be fed to said barrel, said tube and barrel being provided with complementary threads adapted to hold the end of said barrel against said hollow tapered collar, and a plug threaded to engage said tube and adapted to engage said tapered collar to close the tube.

4. As a new article of manufacture, a filler for fountain pens consisting of a tubular member closed at one end, means for securing a closure at the opposite end of the member, said tubular member being provided adjacent its open end with a tapered, downwardly inclined collar to form a seat for such closure and for the end of a fountain pen in the filling of the barrel thereof, upon removal of said closure.

BENJAMIN L. DALL.
